UNITED STATES PATENT OFFICE

169,978

COMBINATION FREEZER AND REFRIGERATOR

George P. Kennedy, Conklin, Mich., assignor to
Borg-Warner Corporation, Chicago, Ill., a cor-
poration of Illinois

Application March 10, 1953, Serial No. 23,973

Term of patent 14 years

(Cl. D67—3)

To all whom it may concern:

Be it known that I, George P. Kennedy, a citizen of the United States, residing in Conklin, in the county of Ottawa, and State of Michigan, have invented a new, original, and ornamental Design for a Combination Freezer and Refrigerator, of which the following is a specification, reference being had to the accompanying drawing forming a part thereof, in which:

Fig. 1 is a perspective view in closed position of a combination freezer and refrigerator embodying my new design; and

Fig. 2 is a perspective view thereof in open position showing the freezer section on the left and the refrigerator section on the right.

The side not shown is the same as the side shown.

I claim:

The ornamental design for a combination freezer and refrigerator, substantially as shown and described.

GEORGE P. KENNEDY.
